[57] ABSTRACT

A device for pressing air into inflatable articles with the aid of one larger and one smaller air container and a valve housing connected therebetween, said valve housing communicating with the article to be inflated. The valve housing is provided with two non-return valves opening up only in the direction towards the valve housing outlet to the article to be inflated, the first one of said valves being arranged at a point between the valve housing inlet opening towards the larger container and the valve housing opening towards the smaller container and the second valve being positioned at a point between said valve housing opening towards the smaller air container and the outlet towards the article to be inflated.

DEVICE FOR PRESSING AIR INTO INFLATABLE ARTICLES

BACKGROUND OF THE INVENTION

The present invention concerns a device intended to press air into inflatable articles such as air mattresses, rubber boats, inflatable furniture and similar objects, said device comprising one larger and one smaller air container having resilient walls.

To inflate air mattresses and similar articles that hold comparatively small volumes of air a number of devices are already known. However, these devices are unsatisfactory when the article to be inflated is larger in size than a common air mattress. Various gas-holding containers then may be used but the contents thereof are only sufficient for a few inflating operations and a new container then must be provided. Pressurized air containers are comparatively expensive and for this reason this solution is not very attractive.

A device affording a good solution to the problem outlined above consists of a bag trapping a sufficiently large volume of air which volume may be forced into one corner of the bag while compressing the bag. The bag corner forms a separate unit from the rest of the bag through a welded seam incorporating an air inlet opening and air is forced into the article to be inflated from this separate corner. Certain manipulations are required to prevent the air from flowing back into the bag through the opening between the bag and the smaller air container formed by the corner during the compression thereof and this necessity for manipulations sometimes gives rise to difficulties, particularly in case and elevated pressure is required in the inflatable object in question.

BRIEF SUMMARY OF THE INVENTION

The purpose of the present invention is to make it possible to inflate articles of the kind referred to in a more efficient and rapid manner. The invention is characterised by a valve housing connected between the larger air container and the smaller air container and having an outlet for the compressed air passing through the valve housing chamber, said valve housing being also provided with a first valve mounted between the larger air container and the valve chamber and with a second valve mounted between the valve chamber and the outlet, said valves both being non-return valves opening only in the direction towards the outlet.

By means of a device in accordance with the invention it is possible to fill articles of various sizes, also those requiring a very large amount of air, in a short time and the desired positive pressure within the article in question is thereafter achieved in a simple and quick manner, making the article firm and steady.

BRIEF DESCRIPTION OF THE DRAWINGS

A few embodiments of the invention will be described more in detail in the following with reference to the accompanying drawings, wherein

FIG. 1 is a plan view of a bag arrangement in accordance with the invention wherein both air containers are formed by one bag as described above.

FIG. 2 illustrates the manner in which the bag arrangement in accordance with the embodiment of the invention illustrated in FIG. 1 is filled with air,

FIG. 3 is a broken view of a second embodiment of the inventive object, wherein the smaller container is separate and attached to the rest of the bag arrangement by means of a screw joint,

FIG. 4 illustrates a third embodiment of the invention according to which the valve housing is provided on the smaller air container and connectable to the larger air container, parts of which have been broken away in this figure,

FIGS. 5, 6, and 7 are longitudinal sections through the valve housing incorporated in the inventive object, the valves being in positions for filling an article directly from the larger air container, for filling the smaller air container from the larger one, and for filling the article from the smaller air container, respectively,

FIG. 8 is a transverse section through the valve housing along line VIII—VIII of FIG. 5,

FIG. 9 is a longitudinal section through the valve housing and a part of the two air containers in accordance with still another embodiment,

FIG. 10 is a side view of the valve housing incorporated in the inventive object in accordance with still another embodiment, and

FIG. 11 illustrates in a perspective view a nipple incorporated in the valve housing of FIGS. 9 and 10.

DETAILED DESCRIPTION OF A PREFERRED EMBODIMENT

The embodiment illustrated in FIGS. 1 and 2 comprises in accordance with the invention a bag 1 made from e.g. plastic-coated cloth, one corner 2 of which having been separated from the remaining area of the bag by means of a welded seam 3. Through the welded seam 3 and an edge 4 of the bag 1 adjacent the welded seam extends valve means including a valve housing 5 which communicates through an air inlet opening 6 with the interior of the bag and is provided with an outlet 7 at the outer face of the bag. The valve housing 5 communicates through an opening 8 with the interior of the separate corner 2. A first flap valve 10 is positioned between the inlet opening 6 and the chamber 9 of the valve housing 5, said flap valve opening up in the direction towards the valve chamber 9. A second flap valve 11 is positioned between the valve chamber 9 and the outlet 7, said valve 11 opening up in the direction towards the outlet. A hose 12 is connectable to the outlet 7 and provided at its outer end with a nozzle 13. The opening 8 debouches directly into the valve chamber 9.

To fill an inflatable article with air, the bag is at first filled in the manner illustrated in FIG. 2, i.e. the bag is opened and swung in a sweeping motion with the bag opening facing forwards. Both hands are then used to gather the mouth portion of the bag and wring it to make the bag air tight. If the article to be filled is empty from the start it is easy to blow the air straight through the valve housing, past the valves 10, 11 and via outlet 7, hose 12 and nozzle 13 into the article by simply squeezing the bag slightly. When the article has been filled sufficiently to make further filling thereof in this manner difficult to perform on account of the counter-pressure in the article to be filled, use is made of the smaller air container, formed by the separate bag corner 2. This container naturally has also been filled with air entering from the larger air container during the filling thereof. It is easier to compress the smaller air con-

tainer than the larger one, and by now squeezing the smaller air container, air is made to enter into the article to be filled, from the smaller container via valve 11, as the first valve 10 acts as an obstacle preventing air from flowing back into the larger container. When air is no longer introduced into the article to be filled the second valve 11 locks as a result of the pressure built up inside the article. The smaller container is again filled from the larger one and the procedure described above is repeated a few times until a sufficiently high pressure has been obtained.

As the smaller air container will often be exposed to more wear and tear than the larger one, it is advantageous if the smaller one be replaced making it unnecessary to discard the entire device. Two embodiments incorporating this advantageous feature are illustrated in FIGS. 3 and 4, respectively, wherein the valve housing 5 is mounted on a larger air container 14 and on a smaller container 15. The larger air containers are illustrated as partly broken away for more clarity of the figures.

In the embodiment illustrated in FIG. 3 the smaller air container 15 is separate and easily replaceable on account of the provision of a connection nipple 16 having internal threads, said nipple being arranged to be screwed onto a pipe socket 17 formed on the valve housing. The pipe socket 17 opens into the valve chamber 9. The smaller container 15 may be attached to the larger air container 14 by means of buttons or in any other way by means of attachment means 18 of known construction.

In accordance with the embodiment illustrated in FIG. 4, the valve housing 5 is attached to the smaller air container 15, and the larger air container 14 may be attached to the housing by means of a nipple 19 fitting a pipe socket 20 on the valve housing 5.

As appears from the embodiment illustrated in FIGS. 5, 6, 7, and 8 a valve housing 5 incorporated in the inventive object comprises two halves 21, 22 assembled for instance by means of glueing. For guidance of the two halves relative to one another during assembly and glueing, the halves are provided with guide pins 23 and mating holes 24. At one end the valve housing 5 is formed with a tubular outlet 7 and at its opposite end it is provided with an inlet opening 6 for admittance of air from the larger air container. Approximately at the centre of the valve housing 5 is positioned the second opening 8 debouching into the smaller container. Adjacent the inlet opening 6 is arranged the first flap valve 10 and the second flap valve 11 is arranged adjacent the outlet 7. Each valve consists of a thin, essentially rectangular plate 25 of plastics presenting at two neighbouring corners coaxial pins 26 mounted in corresponding openings in the valve chamber wall such that the plates may be swung towards and away from their valve seats 27. The plates 25 are provided on their top surfaces with a distance shoulder 28 preventing them from abutting flatly against the wall of the valve chamber. In this manner is ensured that the plates adapt themselves readily to the air flows through the valve housing and also that the valves function extremely well. The valve housing may, as indicated by dash-and-dot lines in FIG. 8, be provided internally with supports 29 for the plates 25, if the latter are thin and slack.

FIG. 5 shows the two valves 10, 11 in open position when the pressure in the article to be filled with air is low and the article is filled directly from the larger con-

tainer 1. In FIG. 6 is illustrated the positions of the valves when the pressure inside the article exceeds the pressure of the larger air container, in which case the second flap valve 11 is closed and the first valve 10 open to allow air to be admitted into the smaller air container 2. FIG. 7 finally, illustrates the positions of the valves when air from the smaller air container 2 is forced into the article. The first flap valve is in this instance closed on account of the pressure in the valve chamber 5 exceeding that in the larger air container 1.

The embodiments of the two air containers illustrated in FIGS. 1 - 4 are imagined made from a plastic-coated cloth surrounding the valve housing which is manufactured from rigid plastics and attached to said housing by means of some adhesive. In practice it has, however, proved to be difficult to make the joint between the wall of the air containers and the valve housing sufficiently tight.

The purpose of the embodiment illustrated in FIGS. 9 to 11 is to remedy this drawback.

In accordance with the embodiment illustrated in FIG. 9 the valve housing 5 is provided adjacent its outlet end 7 with a collar 30 and the outlet end, which is tubular in shape, is provided with external screw threads 31 and with a clamping nut 32 mating therewith. Inside the nut 32 is provided a sealing washer 33 which together with the wall 34 of the larger air container 14 is clamped in air tight position against the collar 30 by means of said nut 32. The outlet end 7 supports a hose 12, which is threaded or screwed onto said end.

The valve housing is in addition formed with a tube socket 17 having screw threads thereon, said tube socket passing through the wall 34 of the container. A sealing washer 35 is arranged inside said wall. The tube socket debouches into the valve housing chamber between valves 10 and 11. A nipple 36, preferably made from weldable plastics, is screwed onto the tube socket 17, said nipple presenting at its inner end a plate 37 to which the wall 38 of the smaller air container 15 is attached, for instance by means of a welded seam. Between the head 39 of the nipple and the container wall 34 is inserted a sealing washer 40 which is arranged, upon tightening of the nipple 36, to be forced together with the container wall 34 against the sealing washer 35, whereby an air-tight joint is formed.

In accordance with the embodiment illustrated in FIG. 10 the inlet end 6 of the valve housing 5 is formed as a pipe joint having internal screw threads mating with the internal screw threads of a tubular nipple 41 which is provided with a clamping nut 42 and a flange 43 positioned inside the container wall 34. The nut urges a washer 44, arranged between said nut and the wall 34, into air-tight abutment against the flange 43. The nipple 36 of the smaller air container 15 has its head 39 screwed onto a pipe socket 17 on the valve housing 5, said socket supporting a sealing washer 45. Also the joint between the smaller container 15 and the valve housing 5 thus becomes air tight.

The invention is not limited to the embodiments as described and illustrated above but various modifications are possible within the scope of the appended claims.

The valves may be designed in a variety of ways without altering the function of the inventive article. The material forming the valve plates need not be plastics.

Instead, the plates may be formed from for instance thin metal. The various configurations of the air containers illustrated should be regarded as preferred embodiments only, not limiting the scope of the invention. The geometrical configuration of the air containers likewise is without essential importance. The material making up the air containers need not necessarily be plastics but some other air-tight material may be used, for instance waxed cloth. Possibly the smaller air container may be provided with spring means tending to keep the container in expanded condition to enable it to be automatically filled with air.

What I claim is:

1. An improved device for pressing air into inflatable articles, said device comprising a larger air container having resilient walls and means defining an opening therein receptive of air for filling same; and a smaller air container having resilient walls and compressible during use to discharge air therefrom, a valve housing connected to said larger air container and said smaller air container means defining a chamber in said valve housing for passage therethrough of pressurized air, means defining an outlet port in said valve housing for said pressurized air, a first valve in said valve housing positioned between the larger air container and said valve chamber, and a second valve in said valve housing positioned between said valve chamber and said outlet port, both said valves being non-return valves opening only in the direction towards said outlet and said smaller air container being connected to said chamber between said valves.

2. An improved device as claimed in claim 1, wherein said valve housing is permanently attached to the wall of said larger air container, wherein the smaller air container is separate from said larger air container, and further comprising connecting means being provided on said smaller air container and connecting means in said valve housing mating with said connecting means on said smaller air container.

3. An improved device as claimed in claim 2, further comprising attachment means for releasably attaching said smaller air container to said larger air container.

4. An improved device as claimed in claim 1, wherein said valve housing is permanently attached to said smaller air container, and further comprising attachment means on said larger air container and attachment means on said valve housing mating with said attachment means on said larger air container.

5. An improved device as claimed in claim 1, wherein said larger air container and said smaller air container comprises a bag of weldable material, a welded seam extending across one corner of said bag dividing the interior volume of said bag into one larger portion forming said larger air container and one smaller portion forming said smaller air container, and means defining openings in said welded seam between said larger air container and said smaller air container and in the outer edge of said smaller air container to receive therein said valve housing in a sealed position.

6. An improved device as claimed in claim 1, wherein said valve housing comprises two half sections joined together.

7. An improved device as claimed in claim 6, further comprising guide means provided on said two valve housing halves, said guide means disposed on the edges

of the housing and consisting of guiding pins and means defining mating apertures receptive of said pins.

8. An improved device as claimed in claim 1, further comprising means connecting said valve housing to said small air container comprising a tubular nipple, made from weldable plastics, on said smaller air container, a plate formed at one end of said nipple to attach the smaller container wall to said nipple, means defining a threaded bore formed at the opposite end of said nipple, a tube socket formed on said valve housing at a point between said two valves, said threaded bore enabling said container to be removably attached to said tube socket.

9. An improved device as claimed in claim 8, wherein said tube socket penetrates into the larger air container wall and is sealed off against the wall of the larger air container.

10. An improved device as claimed in claim 1, further comprising means connecting said larger air container to said valve housing comprising a pipe socket at the inlet end of said valve housing, a tubular nipple on said larger air container, said nipple extending through the wall of said larger air container, a collar flange formed at one end of said nipple and a pipe socket at the opposite end of said nipple, said pipe socket enabling said nipple to be attached to said larger air container wall, whereby said valve housing is removably attachable to said socket.

11. An improved device according to claim 1, wherein both said valves comprise non-return flap valves opening only in the direction towards said outlet port.

12. An improved device as claimed in claim 11, wherein said flap valves comprise thin plates having rectangular configuration, valve seats in said valve housing wherein said plates abut against said seats in sealing positions, and means mounting the plates for pivotal movement comprising two pins positioned at adjacent corners of said plate and mounted in the wall of said valve chamber.

13. An improved device as claimed in claim 12, further comprising means for preventing said plates from opening fully into flat abutment positions against the valve housing wall.

14. A device for forcing gases into inflatable articles comprising a first gas container comprising compressible resilient material and having means defining an opening therein receptive of gas during use for filling said container; a second gas container substantially smaller in volume than said first gas container comprising resilient material and compressible during use to discharge gas therefrom; and valve means in communication with said first and second gas containers and releasably communicable with an inflatable article during use for providing one-way gas communication from said first gas container to said second gas container and one-way gas communication from said second gas container to the inflatable article; whereby gas discharged from said second gas container through said valve means into the inflatable article after compression thereof is replaced from the supply of gas in said first gas container through said valve means as a result of said first container being compressed, thus causing a pressure difference between said first and second gas containers and wherein said valve means comprises a valve housing, means defining an inlet port in communication with said first gas container and an outlet port

in communication with the inflatable article, means defining a valve chamber between the inlet and outlet ports and in communication with said second gas container, a first one-way valve disposed between said inlet

port and said valve chamber and a second one-way valve disposed between said valve chamber and said outlet port.
